UNITED STATES PATENT OFFICE

2,667,384

OIL BURNER

Herman Phipps, Montebello, Calif.

Application April 13, 1951, Serial No. 220,870

2 Claims. (Cl. 299—140)

1

This invention relates to oil burners, and particularly to burners having a non-rotary nozzle.

The important function of an oil burner of this character is to ensure that the fuel is uniformly and finely subdivided when it is ejected from the nozzle. This "atomization" is usually effected by the aid of air or steam pressure.

It is one of the objects of this invention to provide an improved burner of this character.

It is another object of this invention to ensure a finer and more complete subdivision of the fuel in the form of vapor, while yet utilizing a simple and inexpensive structure.

It is still another object to provide a structure in which the nozzle passageways are left clean and unobstructed even upon long continued use of the burner.

This invention possesses many other advantages, and has other objects which may be made more clearly apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is an elevation of an oil burner incorporating the invention shown as installed in a fire box;

Fig. 2 is a front elevation of the burner;

Fig. 3 is a longitudinal, sectional view of the oil burner shown in Fig. 1; and

Fig. 4 is a fragmentary view showing the projection of the subdivided fuel from the discharge end of the nozzle.

The outer wall 1 of a fire box is provided with appropriate openings 2 and 3 for the admission of a fuel pipe 4 and a steam pipe 5 into the fire box proper. The heat-resistant lining of the fire box has been omitted from the illustration for the sake of clarity.

The fire box may be used for the generation of steam in the boiler in a well understood manner. For this purpose, the oil burner is provided with a nozzle structure 6. This nozzle structure 6 has a discharge end formed by the aid of the parallel walls 7 and 8 (Figs. 2 and 3). These parallel walls define a narrow exit or discharge passage 26 for the atomized or subdivided fuel. This nozzle passage has a width which diverges toward the outlet end, as shown most

2

clearly in Fig. 4. In use, the spray of fuel mixture is ejected from the discharge end in a diverging stream, as indicated by the phantom lines 9 of Fig. 4. The fog or spray formed in this way projects for a substantial distance beyond the discharge end 10 of the nozzle before it ignites to form the burner flame 11.

The inlet end of the nozzle 6 is defined by a cylindrical conduit 12 to form a chamber 25 which merges into the inner constricted end of the nozzle 6. The cross-section area of this chamber is much greater than any cross-section of the nozzle opening 26.

In the present instance, steam may be supplied to the nozzle 6 under a substantial pressure to urge the atomized fuel through the nozzle 6. For this purpose, the conduit 5 is connected to a source of steam supply. This conduit 5 is substantially coaxial with the conduit 12.

The passage of the steam and the oil to the conduit 12, and thence through the nozzle 6, is effected by the aid of a tubular member 13 of smaller diameter than the conduit 12, and shown as joined integrally therewith. The inlet end 14 of the tubular member 13 is shown as somewhat flared, and faces the outlet end of the jet member 15 into which is threaded the steam conduit 5. This jet member 15 has an opening converging toward the inlet end 14, and spaced slightly therefrom.

A housing member 16 surrounds the tubular member 13, and forms an annular space 17 between the members 13 and 16. The left-hand end of the housing member 16 provides a threaded aperture for the threaded right-hand end of the conduit 12. The right-hand end of housing 16 similarly threadededly engages the jet member 15. These threads form a substantially fluid-tight seal.

A supply of oil is effected into the annular passage 17 by the aid of an elbow structure 18. This elbow structure 18 has a rearwardly directed threaded end 19 into which the oil supply conduit 4 is threaded. The fuel passage 20, formed in the elbow 18, curves downwardly to form an exit 27 for the fuel at a distance substantially spaced forwardly from the inlet end 14 of tubular member 13. In this way, the fuel must travel, as indicated by the arrows 21, through the annular passageway toward the rear before it can enter over the lip of the opening 14. The fuel contacts the outer surface of tubular member 13, where it is preheated, due to the transfer of heat through this member. The heat is derived both

from the steam and heat conduction within the fire box through the nozzle structure.

As the liquid fuel flows over the lip 14, the steam passing through the jet member 15 and the tubular member 13 picks up the fuel and mixes with it within the tubular member 13. The flow is indicated by arrows 28.

Expansion of the mixture occurs within the chamber 25, since its cross-section area is greater than the cross-section area of the tubular member 13. Substantially complete subdivision or atomization is effected in this manner. The fuel, furthermore, is preheated by its passage over the tubular member 13 before the fuel enters this tubular member.

Ordinarily, a pump is required to urge the fuel at a relatively low pressure through the annular passage 17. The expanded atomized fuel within conduit 12 is urged into the inlet end of the narrow passage defined by walls 7 and 8, and diverges in the manner indicated in Fig. 4. The feeding of the oil to the annular passage 17 at a place forward of the inlet end 14 of tubular member 13 greatly facilitates the ultimate fine subdivision of the fuel, and this effect is augmented by the expansion of the mixture of fuel and steam within conduit 12. Due to the diverging nozzle passage-way, the walls 7 and 8 remain clean and free of deposits even after continued use.

The inventor claims:

1. In an oil burner: a nozzle structure having means forming a discharge passageway, a chamber communicating with said discharge passageway, and an elongate member having a through aperture forming an inlet passageway communicating with said chamber, said chamber forming an abrupt and substantial enlargement at said inlet passageway; said inlet passageway terminating in an intake opening formed by a flared end of said elongate member and defining an end surface between the exterior and interior of said elongate member; a housing; means securing said nozzle structure to said housing and positioning said elongate member in said housing to form a passageway surrounding said elongate member, the intake opening being within the housing; means supplying fuel into said surrounding passageway at a place remote from said intake opening and adjacent said elongate member; and a conduit for supplying a fluid medium under pressure into said intake opening and for drawing fuel around said end surface, said conduit converging and forming an opening in said housing aligned with said intake opening, and spaced substantially therefrom, the diameter of said con-

duit opening being less than the diameter of said intake opening.

2. In an oil burner: a hollow housing member opening at opposite ends thereof, said housing member having means forming a passage for supplying fuel, said passage opening into the interior of said housing member adjacent to one of said ends of said housing member; an integral nozzle structure having means forming a discharge passage, said structure having means forming a central mixing chamber, said structure also having means forming a reduced elongate tubular inlet member communicating with said central chamber, said central chamber forming an abrupt and substantial enlargement at said tubular inlet member; means securing said nozzle structure and said housing member together, said nozzle structure being telescopingly received into said one end of said housing member, the tubular inlet member terminating adjacent the other end of said housing member; said tubular inlet member cooperating with said housing member to define an annular space; the end of said tubular inlet member being outwardly flared and defining a lip around which fuel is adapted to pass; and conduit means at the other end of said housing member for supplying a fluid medium under pressure, said conduit means being aligned with said tubular inlet member, said conduit converging in a direction toward said tubular inlet member and forming an opening spaced substantially from said end of said tubular inlet member, the opening of said conduit means being of a size less than that of the flared end of said tubular inlet member.
